Primary Examiner — Calvin E Vansant*Assistant Examiner* — Mark T. Philipp(74) *Attorney, Agent, or Firm* — Workman Nydegger**(57) CLAIM**

The ornamental design for a compressor shell, as shown and described.

DESCRIPTION

FIG. 1 is a top, front, right perspective view of a compressor shell in accordance with the present invention;

FIG. 2 is an elevated right side view thereof;

FIG. 3 is an elevated rear view thereof;

FIG. 4 is an elevated left side view thereof;

FIG. 5 is an elevated facing thereof;

FIG. 6 is a top plan view thereof;

FIG. 7 is a bottom plan view thereof; and,

FIG. 8 is a top, front right perspective view of the compressor in an ordinary use environment.

The broken lines depict portions of the article that form no part of the claimed design.
